(57) **CLAIM**

The ornamental design for a clip-on lens carrier for smart eyewear, as shown and described.

DESCRIPTION

FIG. 1 is a front elevational view of a clip-on lens carrier for smart eyewear for the new design;

FIG. 2 is a rear elevational view thereof;

FIG. 3 is a side elevational view, wherein the other side is a minor image thereof;

FIG. 4 is a bottom plan view thereof;

FIG. 5 is a top plan view thereof;

FIG. 6 is a front perspective view thereof; and,

FIG. 7 is a rear perspective view thereof.
